UNITED STATES PATENT OFFICE.

BRUCE K. INGLIS, OF MILWAUKEE, WISCONSIN, ASSIGNOR OF ONE-HALF TO CLEMENT W. INGLIS, OF MILWAUKEE, WISCONSIN.

OIL BURNER.

Application filed June 14, 1928. Serial No. 115,764.

This invention relates in general to improvements in the art of heating, and relates more specifically to improvements in the construction and operation of hydrocarbon burners for furnaces, boilers or the like.

An object of the invention is to provide a new and useful hydrocarbon burner which is simple in construction and efficient in operation.

10 Some of the more specific objects of the invention are as follows:—

To provide a highly efficient oil burner which may be manufactured, sold, and operated at relatively moderate cost.

15 To provide a burner for hydrocarbons, in which danger of explosions is entirely eliminated, and which may be successfully manipulated and operated by a novice.

To provide a burner operable with a forced air draft, in which continuous operation is assured even when the normal air supply fails to function.

20 To provide simple and efficient means for increasing the economy of oil burners or the like, by pre-heating the air delivered to such devices.

To provide an extremely simple and compact burner structure which may be readily assembled and dismantled.

25 To provide improved means for quickly and effectively starting and interrupting the operation of oil burners or the like.

To provide various other improvements in the details of construction and operation of oil burners especially adapted for domestic service.

30 A clear conception of an embodiment of the present invention and of the mode of installing and of operating devices constructed in accordance therewith, may be had by referring to the drawing accompanying and forming a part of this specification in which like reference characters designate the same or similar parts in the various views.

45 Fig. 1 is a central vertical section through one form of the improved oil burner, showing the same applied to a fragment of a furnace.

Fig. 2 is a part sectional front view of a fragment of the burner illustrated in Fig. 1.

50 Fig. 3 is a central vertical section through a fragment of the improved burner, showing the motor controller in position to admit atmospheric air to the combustion chamber.

55 As specifically illustrated, the improved oil burner comprises in general a main inner

casing 2 having an integral outwardly flaring rim 26 at its upper open end; fuel oil and air distributing elements supported by and disposed centrally within the casing 2; a tubular supporting member 3 rigidly attached at one 60 end to the casing 2 and providing an air supply conduit communicating with the lower interior thereof; an auxiliary outer casing 4 rigidly attached to the opposite end of the member 3; a motor driven blower or fan 5 and 65 motor control mechanism 29 removably associated with the casing 4; and a universally adjustable support for the tubular member 3 and the elements associated therewith. The main inner casing 2 and the fuel and air distributing elements are disposed below the combustion chamber 15 of a furnace, and the annular rim 26 of the casing 2 is adapted to cooperate with a central spreader plate 12 supported from the casing 2 by means of a 70 column 13 to effectively distribute the combustible gases and the flame throughout the chamber 15.

The oil and air distributing cup or element 11 comprises a horizontal plate having air distributing openings 19 therein, and a series of three concentric annular walls 16, 18, 21 formed integral with and flaring upwardly from the perforated plate. The plate of the element 11 rests upon an annular ledge with- 80 in the casing 2, and the inner walls 16, 18 co- 85 operate to form an upwardly open annular recess. A piece of asbestos or other porous material 22 which rests upon an inwardly projecting ledge of the wall 18, divides the 90 annular recess into a lower annular chamber 20 and an upper recess portion which is filled with porous material 17. The holes 19 penetrate the element 11 on opposite sides of the outer wall 21, and the spreader plate is dis- 95 posed directly above the annular bed of porous material 17.

An oil supply pipe 6 communicates with the annular chamber 20 below the porous material 17, and extends outwardly through the tubular member 3 to a suitable source of oil located above the level of the burner. The quantity of oil delivered through the pipe 6 is controllable either by means of a manually operable valve 39 having an indicator 40, or 100 by means of an automatically operable thermostat-controlled valve. A safety stop valve 38 in the pipe 6 is automatically operable to shut off the flow of oil through the pipe, in case the flame is extinguished and the oil 105 110

supply valve 39 remains open. Under such conditions of operation, the oil delivered from the top of the porous material 17, flows through the member 3 and the outer casing 4 until it strikes the dam 23 whereupon the oil is deflected through a trap 24 into a bucket 25. As the bucket 25 becomes sufficiently filled with oil to actuate the valve 38, this valve is automatically closed through the linkage 27. A pipe 14 for supplying gas for ignition purposes, also extends through the casing 4 and the tubular member 3, and communicates with the medial portion of the bed of porous material 17 within the distributor recess. The auxiliary outer casing 4 has a front air inlet opening which is normally sealed by the motor control mechanism 29, as shown in Fig. 1. The casing of the mechanism 29 is mounted upon a pivot 33, and is provided with an arm 34 and an adjustable weight 32 for elevating the mechanism to the position shown in Fig. 3 when the blower actuating circuit is interrupted. This action is automatically effected by means of an electro-magnet 44 having an energizing winding in series with the blower actuating circuit, and cooperating with an adjustable plate 46 attached to the bottom of the casing 4. The weight 32 is adjustable along the arm 34, and is sufficient to over-balance the weight of the control mechanism 29. The extent of upward movement of the control mechanism 29 is limited by virtue of the striking of the end of the arm 34 against the air inlet casing 35. The outer casing 4 also has a lateral tubular extension 43 which provides a support for the blower 5 and its driving motor 31. The discharge pipe 28 of the blower 5 fits within the tubular extension 43 the bore of which may be slightly tapered. The suction casing 35 of the blower 5 is preferably located adjacent to a heated wall 41 of the furnace, and has a plate 36 adjustably secured thereto adjacent to an atmospheric air inlet, by means of adjusting screws 37. Other air inlet openings 45 formed in the supporting element 8 or in the wall 41 of the furnace, connect the interior of the furnace directly with the suction casing 35. The blower 5 is direct connected with the variable speed electric motor 31, the speed of the motor being controllable by means of a rheostate 30. The main switch 42 for the motor circuit forms part of the control mechanism 29 which is provided with ordinary plug connectors for hooking in on a convenient power line.

The burner support comprises a spherical element 7 attached to the medial portion of the tubular member 3 and coacting with a supporting element 8 secured to the wall 41 of the furnace. A clamping member 9 coacting with the element 7 cooperates with the clamping bolts 10 to lock the tubular member 3 in any desired position of adjustment. By means of the universal support just de-

scribed, the cup element 11 may be readily positioned so that the oil is uniformly discharged from the top of the bed of porous material 17 in a horizontal plane, and in equal quantities at all points around the axis of the 70 distributing bed.

During normal operation of the burner, the several parts are positioned as shown in Fig. 1, and oil under pressure is being delivered to the annular chamber 20 through the pipe 6 75 and control valve 39. The blower 5 is being operated by the motor 31 to withdraw pre-heated air from within the furnace through the openings 45 and directly from the atmosphere through the gap between the heated 80 wall 41 and the adjustable plate 36. This pre-heated air is delivered under pressure through the pipe 28, the member 3 and the openings 19 as well as through the central opening of the element 11, upwardly toward 85 the stationary spreader plate 12 and outwardly over the rim 26 of the casing 2. The film of pre-heated air traveling outwardly over the fuel oil which oozes upwardly through the porous material 17, picks up the 90 oil and forms a combustible mixture which is ignited as it passes over the rim 26 and continues to burn as it advances upwardly through the combustion chamber 15. During such normal operation of the burner, the electro-magnet 44 is energized and holds the control mechanism down over the front opening of the casing 4, so that no other than pre-heated air under pressure can be admitted to the combustion chamber 15. By regulating 95 the speed of the motor 31, the position of the plate 36 and the setting of the control valve 39, the degree of heat generated by the burner may be readily controlled.

If the power should fail, thereby causing 100 the motor 31 and the blower 5 to stop, the electro-magnet 44 will be de-energized this causing the weight 32 to become effective to position the control mechanism as shown in Fig. 3. Such adjustment of the mechanism 110 29, effects automatic admission of air by the stack suction, directly to the combustion chamber 15 through the casings 4, 2 and the member 3. The operation of the burner will thus continue at reduced efficiency, until the 115 power is again available to operate the blower 5.

By admitting the ignition gas through a pipe 14 directly into the porous bed, the material 17 will deliver the gas in the form 120 of an annular jet thus insuring complete ignition when starting. This arrangement of the pilot light, also enables the use of gas alone for heating in cases of emergency or when limited heat is required. The safety-valve 38 automatically shuts off the oil supply when the flame is extinguished thus making the entire apparatus extremely safe in operation.

The universal support for the burner en- 130

ables proper adjustment of the cup element 11 so as to insure uniform feeding of the oil, and also permits installation of the burner in standard furnaces. The casings 2, 4, the member 3 and the element 11 may be conveniently manufactured, assembled and dismantled, and the simplicity of the burner enables manufacture and sale of the device at extremely moderate cost.

10 It should be understood that it is not desired to limit the invention to the exact details of construction and operation herein shown and described, for various modifications within the scope of the claims may occur to persons skilled in the art.

15 It is claimed and desired to secure by Letters Patent:—

1. In combination, a burner comprising a fuel distributing cup, a member forming a 20 conduit, said cup being supported upon an end of said member, and a universally adjustable support for said member, said support being formed for attachment to a furnace wall and being adjustable to enable both 25 lateral and longitudinal shifting of said cup within the combustion chamber of the supporting furnace.

2. In combination, a burner comprising a fuel distributing cup, a member forming a 30 conduit, said cup being supported upon one end of said member, a blower supported upon the opposite end of said member, and a universally adjustable support for the medial portion of said member, said support being 35 formed for attachment to a furnace wall and being adjustable to enable both lateral and

longitudinal shifting of said cup within the combustion chamber of the supporting furnace.

3. In combination, a burner, a member 40 forming a conduit, a blower for supplying air to said burner through said conduit, a motor for driving said blower, motor control means, said member having an air inlet opening and said control means being movably associated with said opening, a weight normally tending to move said control means to uncover said opening, and electro-magnetic means energized by the actuating current of said motor to normally resist the opening 45 movement of said control means, said weight being effective to uncover said opening upon de-energization of said electro-magnetic means.

4. In combination, a burner, a member 55 forming a conduit, a blower for supplying air to said burner through said conduit, a motor for driving said blower, said burner being supported upon one end of said member and said blower and motor being supported upon the opposite end thereof, motor control means, said member having an air inlet opening and said control means being movably associated with said member at said opening, and means for moving said control 60 means to uncover said opening and to admit atmospheric air to said burner through said opening when the current for operating said motor is interrupted.

In testimony whereof, the signature of the 70 inventor is affixed hereto.

BRUCE K. INGLIS.
